(57) **CLAIM**

I claim the ornamental design for an orthopaedic implant, as shown and described.

DESCRIPTION

FIG. 1 is a perspective view of an orthopaedic implant showing my new design;

FIG. 2 is a left side elevation thereof;

FIG. 3 is a right side elevation thereof;

FIG. 4 is a front elevation thereof;

FIG. 5 is a rear elevation thereof;

FIG. 6 is another front elevation thereof in an alternate arrangement; and,

FIG. 7 is a rear elevation thereof.

The broken lines shown in FIG. 7 define the bounds of the claimed design and form no part thereof.
